AUTOMATIC HYDRAULIC CROSSING SIGNAL

Filed July 12, 1930

UNITED STATES PATENT OFFICE

JOHN A. MUELLER AND LEO H. MUELLER, OF FARMINGTON, MISSOURI

AUTOMATIC HYDRAULIC CROSSING SIGNAL

Application filed July 12, 1930. Serial No. 467,595.

This invention relates to certain novel improvements in automatic hydraulic crossing signals, and has for its principal object the provision of an improved construction of this character which will be highly efficient in use and economical in manufacture.

It is among the several objects of our invention to provide an improved construction of the character described herein which will 10 be simple in construction and positive in operation.

A further object of the invention is the provision of a railway crossing signal embodying gate arms which are lowered into 15 warning position by a hydraulically operated mechanism actuated by the wheels of a train approaching the crossing and which will remain in warning position until the train has passed the crossing when said warning 20 arms will be automatically raised by a mechanism embodied in the invention.

Other objects will appear hereinafter.

The invention consists in the novel combination and arrangement of parts to be hereinafter described.

The invention will be best understood by reference to the accompanying drawings, showing the preferred form of construction and in which:

Fig. 1 is a side elevational view of a part of the crossing gate mechanism embodied in our invention;

Fig. 2 is an enlarged elevational detail view partly in section of a part of the mechanism shown in Fig. 1;

Fig. 3 is a side elevational view of a preferred form of the track mechanism embodied in our invention;

Fig. 4 is a sectional view taken substantially on the line 4—4 in Fig. 3; and

Fig. 5 is a diagrammatical view of one form of warning mechanism operable by our invention.

Referring to the drawing wherein a preferred form of construction of our invention is illustrated, indicated at 10 are railway rails supported on ties 11 embedded in the rail bed 12 and indicated at 13 is a highway crossing over the railway track. Our invention includes a plate 14 which is disposed

parallel to the rails 10 and attached to one of the rails by means of clamps 15 and 16 which are attached to the plate 14 by means of suitable bolt and nut structures 17. Formed integrally with the plate 14 is a shaft 18 on which is mounted for rocking movement a collar 19 carrying arms 20 and 21. A cotter key 22 or the like is provided in a suitable opening formed in the shaft 18 for securing the collar 19 and arms 20 and 21 in position on the shaft 18. The arm 20 includes a rightangularly extending portion 23 on which is rotatably mounted a ball race 24. As best shown in Fig. 4, the ball race 24 is disposed adjacent the edge of the rail 10 so that the wheels 25 of the train will engage the ball race 24 thereby depressing the arm 20 and causing arm 21 to actuate the mechanism now to be described.

In this connection we provide heads 26 on the arm 21 which heads have abutting engagement with head portions 27 provided on plungers 28 and 32. The plungers 28 and 32 carry pistons 29 which are disposed in cylinders 30 and 33 and it is manifest that when the wheels of the train engage the ball race 24 from the left as seen in Fig. 3, arms 21 will actuate plunger 28 thereby moving piston 29 inwardly in cylinder 30 while plunger 32 will remain stationary during this movement of plunger 28. Conversely, when the wheels of the train successively engage the ball race 24 from the right, as seen in Fig. 3, plunger 32 will be actuated forcing its attached piston 29 inwardly in cylinder 33. It is understood that the track mechanism of our invention just described is provided in the railway track structure at both sides of the highway crossing 13 and a suitable distance therefrom so that the mechanism now to be described will be actuated before the engine of the train arrives at the highway crossing.

A discharge outlet 34 is provided in each of the pistons 30 and 33 and controlling these outlets 34 are valves 35 preferably of the ball and spring type as indicated at 35. The discharge outlets 35 communicate with fluid conducting pipes 36 which lead to cylinders 37 which are associated with the crossing gate

mechanisms presently to be described. In the use of our invention we employ a liquid preferably an oil in the cylinders 30 and 33 and it is manifest that when the piston 29 in either of these cylinders is actuated in the manner described above, the oil will be driven out of the cylinder through the discharge valve 35, through pipes 36 and ball valves 38 provided therein to the cylinders 37. Disposed in the cylinders 37 are pistons 39 to which are attached arms 40 and it is manifest that as the oil is driven into the cylinders 37 the pistons 39 will be raised thereby raising the arms 40. As shown in Fig. 1, the arms 40 constitute parts of the crossing gate mechanisms which are arranged in pairs on opposite sides of the railway track so that the gate arms 41 may be lowered across the highway 13 in a manner presently to be described. As the oil from pipe 36 is forced into the cylinders 37 the pistons 39 are raised until they reach a point above the overflow openings 42 provided in the cylinders 37. It is manifest, therefore, that when the pistons 39 reach a point above the overflow openings 42 any additional oil pumped into the cylinders 37 by the action of pistons 29 will flow out of the overflow openings 42 through pipes 43 to overflow tanks 44. The overflow tanks 44 are connected to return pipes 45.

The overflow tanks 44 may be supported in any suitable manner such as on the blocks 46 which may be of any suitable material, for example, concrete, and the blocks 46 preferably support uprights 47 which are attached thereto by bolt and nut structures 48.

Provided in the arms 40 are teeth 49 which engage teeth 50 formed in gears 51 which are mounted on and keyed to shafts 52 by means of keys 53. The shafts 52 are secured in suitable bearing surfaces provided in the uprights 47 and mounted on and keyed to the shafts 52 are the gate arms 41 which carry counterbalances 54 which are attached to the arms 41 in any suitable manner. When the arms 40 are moved upwardly by the action of the pistons 39, in the manner described above, it is manifest that the teeth 49 will engage the teeth 50 on the gears 51 and the gate arms 41 will therefore be lowered into horizontal position across the highway 13. After the train has passed the track mechanism shown in Figs. 2 and 3 and therefore after the wheels of the train have ceased to actuate the plungers 28 and 32, the counterbalance weights 54, will raise the gate arms 41 into vertical position and it is apparent that as the gate arms 41 are raised from horizontal position to vertical position the arms 40 will be lowered and pistons 39 moved downwardly in the cylinders 37. As the pistons 39 are moved downwardly in the pistons 37 part of the oil in the pistons 37 is forced out of these pistons through outlet connections 55 to the tank 44 from which the oil is again

distributed to the return pipes 45 and cylinders 30 and 33.

While it is understood that any suitable warning signals may be provided on the gate arms 41, such as red signal lights, in Fig. 5 we have shown an arrangement for associating our invention with an electric warning bell. In this instance we mount a bell or gongs 56 of any approved type on each of the uprights 47 and one terminal of each of these bells is connected by means of conducting element 57 to a suitable source of electricity such as a battery or the like 58. A conducting element 59 connects the battery 58 to a movable contact which has abutting engagement with the arm 40. It is manifest, therefore, that when the arm 40 is raised it will abut the movable contact 60 and the contact 60 will engage the stationary contact 61 thereby completing a circuit to the bell or gong 56 through the conductor 62 and thus cause the bell to sound a warning signal.

From the foregoing description of our invention it is manifest that we have provided an improved automatic crossing signal construction which will be positive and reliable in use while being economical in manufacture and operation.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

1. In fluid pressure operated crossing signals, a track mechanism comprising a plate, brackets for securing said plate to a rail, a bearing boss on said plate extending right-angularly from the rail when the plate is installed, a rockable member on said boss and including an arm extended toward, and right-angularly with respect to, the rail, a ball race on said arm adapted to be engaged by the wheels of a vehicle passing over the rail, said rockable member having heads on the end thereof opposite said arm, and means engageable by said heads for operating said signals.

2. In fluid pressure operated crossing signals, a track mechanism comprising a plate, brackets for securing said plate to a rail, a bearing boss on said plate extending right-angularly from the rail when the plate is installed, a rockable member on said boss and including an arm extended toward, and right-angularly with respect to, the rail, a ball race on said arm adapted to be engaged by the wheels of a vehicle passing over the rail, said

rockable member having heads on the end thereof opposite said arm, and means engageable by said heads for operating said signals, said last named means including a fluid pressure pump on each side of said rockable member, each of said pumps including a spring actuated piston plunger engageable by one of said heads.

In testimony whereof we affix our signatures.

JOHN A. MUELLER.
LEO H. MUELLER.
